UNITED STATES PATENT OFFICE.

BERKEY E. COVER, OF CHICAGO, ILLINOIS, ASSIGNOR OF ONE-HALF TO WILLIAM G. KEITH, OF CHICAGO, ILLINOIS.

PUBLIC-SPEAKING TELEPHONE RECEIVER.

Application filed July 1, 1921. Serial No. 481,782.

To all whom it may concern:

Be it known that I, BERKEY E. COVER, a citizen of the United States, residing at Chicago, in the county of Cook and State of Illinois, have invented certain new and useful Improvements in Public-Speaking Telephone Receivers, of which the following is a specification.

The object of this invention is to provide a telephone receiver suitably and efficiently protected for out-of-doors installation and capable of being adjusted to increase or decrease the volume of sound without disassembling any of the parts so that the instrument, when provided with a suitable amplifying horn, may be employed as a public speaker to reproduce in public places any sounds that may be transmitted thereto.

My invention is adapted to be installed on a pole at a street corner for reproducing a speech being delivered in a public hall at some distant location so that the speech may be heard distinctly by a large gathering of persons adjacent the pole; and many of these instruments may be so installed and connected to reproduce the same speech so that a speech being delivered at some location may be reproduced simultaneously at many different places and thereby be given wide spread distribution.

It is desirable that an instrument of this kind should be capable of adjustment after it has been installed without requiring that it be taken down or that any of its parts be disassembled because the installation will ordinarily be made on a pole or some other support where it is not always conveniently accessible; and for this reason my invention has for its object to provide the instrument with means whereby it can be easily adjusted to reproduce sounds in a desired tone and volume by manipulating certain adjusting means on the outside of the weather-proof enclosing casing.

It is also desirable that an instrument of this kind should be capable of adjustment to any desired angle or inclination to direct the sound in any desired direction and for this purpose my invention has for its object to provide a bracket mounting for the casing to furnish a universal connection so that the horn may be pitched in any position.

Another object of the invention is to

prevent the diaphragm from shifting its position and at the same time to avoid stiffness and rigidity and permit the diaphragm to vibrate freely as required for satisfactory reproduction.

In the accompanying drawings I have illustrated a selected embodiment of the invention and referring thereto

Fig. 1 is a plan view of the invention the horn being omitted.

Fig. 2 is a sectional view on the line 2-2 of Fig. 1.

Referring to the drawings the invention comprises a metal casing 3 having an ear 4, a bracket arm 5 pivotally connected to said ear by a bolt 6 and a support 7, pivotally connected to the arm 5 by a bolt 8. The arm 5 and likewise the support 7 may be of any size and shape to adapt the instrument for different installations but it will be found that a support such as the disk illustrated may be used for many installations since it can be secured in place by screws, bolts, nails, wire or other fastening means to a wall, a pole or other fixed support.

The casing is conveniently conical in shape and a diaphragm 9 is secured between the clamping ring 11 and the front plate 10 which form a housing located in the large end of the casing. The diaphragm is arranged between rubber rings 12, 12 located on opposite sides of the diaphragm at the periphery thereof and engage the diaphragm to hold the latter securely between the clamping ring and front plate of the housing which are secured together by screws 13. The rings hold the diaphragm firmly but yieldingly so that it can vibrate freely and to prevent it from shifting position I provide the diaphragm housing with studs 14 enclosed in rubber tubes 14' which fit in openings provided for them in the diaphragm. These studs are located preferably at diametrically opposite points on the front plate of the diaphragm housing and they effectively prevent the diaphragm from shifting position; and since they are enclosed in rubber tubing the diaphragm will be sound insulated therefrom so that any movement of the diaphragm on the studs will not interfere with the reproduction.

The diaphragm housing is held in the larger end of the casing by a brass facing plate 15 which is secured to the

2
casing by screws 15' and a rubber gasket 16 is interposed between the plate 15 on one side and the casing and front plate 10 of the diaphragm housing on the other side. The diaphragm housing is flush with the outer end of the casing and it is provided with a centrally disposed tubular neck 17 which projects through the gasket and the facing plate 15 and may be exteriorly threaded to receive a suitable amplifying horn.

10 A magnet housing 18 is screw threaded in the clamping ring 11 and the pole pieces 19 of the magnets 20 project through the housing which is provided with a block 21 to 15 form a support for said pole pieces. The permanent magnet 22 projects rearward from the magnet housing 18 and a bolt 23 passes through the permanent magnet, the pole pieces and the supporting block, which 20 is a rigid part of the magnet housing, to rigidly secure these parts together. A terminal block 24 is secured in the permanent magnet and wire leads 25, 26 are connected to said block and to terminals 25', 26' on 25 the casing. Wires 27, 27' are also connected to the terminal block and to the magnets.

30 The rear end of the permanent magnet is supported in a yoke 28 carried on a rod 29 which projects through the rear end of the 35 casing and is provided with a wing nut 30 to facilitate adjustment. A set screw 31 in the casing is arranged to bear on the rod 29 to secure the latter in adjusted position. A brass washer 32 is fastened securely on a 35 felt washer 33 against the rear end of the casing by screws 34 to make the casing weather-tight around the rod 29.

40 My invention provides a telephone receiver in which all of the operating parts are efficiently protected against the weather so that it can be used out-of-doors under all 45 conditions and in any place. The bracket arm provides a convenient means for supporting the casing in any adjusted position whereby the horn may be tilted to direct the sound in any desired direction which makes it convenient for use as a public speaker when installed on a street pole or other out-of-door support. The magnets can be easily 50 adjusted relative to the diaphragm by loosening the locking screw 31 and operating the wing nut 30 to adjust the magnet housing in the diaphragm housing in which it is screw threaded. This adjustment can be made to 55 increase or decrease the volume and quality of the sound reproduced and when the desired adjustment is obtained the set screw 31 is turned to locking position to permanently maintain the parts in the position to 60 which they have been adjusted. It is often desirable to make this adjustment or to readjust the parts after the instrument has been 65 installed and since the instrument cannot always receive constant attention when it is used for public speaking in public places it

is highly desirable not only that this adjustment should be easily made without disassembling any of the parts but also that it should be permanently maintained after it is made, and both of these objects are attained by my invention in a simple, efficient and convenient manner. The casing forms a protection for the operative parts of the instrument so that it is adapted for universal use out-of-doors under all conditions of 75 weather and in all seasons of the year.

80 My invention is not only useful for reproducing speeches, notices, announcements, and in fact any kind of sounds for any purpose, but it has many special uses such as furnishing music for skating ponds and for many other purposes.

85 I am aware that changes in the form, proportion and arrangement of parts of my invention may be made to adapt it for different purposes and different installations and I therefore reserve the right to make all such changes as fairly fall within the scope of the following claims.

90 I claim:

1. The combination of a casing, a telephone receiver supported in the casing and comprising a diaphragm and a magnet, a housing for the diaphragm provided with a neck to receive a horn, a housing for the magnet, and means connected to said magnet housing and projecting through the casing and adapted to be operated to adjust the magnet and diaphragm relatively to each other.

100 2. The combination of a casing, a telephone receiver supported in the casing and comprising a diaphragm and a magnet, a housing for the diaphragm secured in one end of the casing and provided with a neck projecting from the casing and adapted to receive a horn, a housing for the magnet, and means operating through the opposite end of the casing and connected to the magnet housing for adjusting the magnet housing in the diaphragm housing to adjust the diaphragm and magnet relatively to each other.

110 3. The combination of a casing, a telephone receiver supported in the casing and comprising a diaphragm and a magnet, a diaphragm housing secured in one end of the casing and provided with a centrally disposed neck to receive a horn, a magnet housing threadedly engaging the diaphragm 120 housing, a rod operating through the other end of the casing and connected with said magnet housing for adjusting the magnet housing in the diaphragm housing, and means for locking said rod in adjusted position.

125 4. The combination of a casing, a telephone receiver supported in the casing and comprising a diaphragm and a magnet, a diaphragm housing comprising a front 130

- plate and a clamping ring secured in one end of the casing, said front plate having a centrally disposed neck to receive a horn, a face plate secured to the casing over said diaphragm housing, a magnet housing screw threaded in the clamping ring of the diaphragm housing, and means operating through the other end of the casing and connected to the magnet housing to adjust said housing in the diaphragm housing for adjusting the diaphragm and magnet relatively to each other.
5. The combination of a casing, a telephone receiver supported in the casing and comprising a diaphragm and a magnet, a diaphragm housing supporting the diaphragm and secured in one end of the casing, a magnet housing supporting the magnet and threadedly engaging the diaphragm housing, a permanent magnet secured to the magnet housing, and a rod connected to the permanent magnet and projecting through the other end of the casing and adapted to be operated to adjust the magnet housing in the diaphragm housing and the magnet relatively to the diaphragm.
6. The combination of a casing, a telephone receiver supported in the casing and comprising a diaphragm having one or more openings therein, a housing, sound insulating means engaging the margin of the diaphragm for supporting the diaphragm in the housing, and studs on the housing projecting into said openings to prevent the diaphragm from shifting position.
7. The combination of a casing, a telephone receiver supported in the casing and comprising a diaphragm having one or more openings therein, a housing, sound insulating means engaging the margin of the diaphragm for supporting the diaphragm in the housing, studs on the housing projecting into said openings, and coverings on the studs to sound insulate the diaphragm from the studs.
8. The combination of a casing, a telephone receiver supported in the casing and comprising a diaphragm having one or more openings therein, a housing, rubber rings arranged on opposite sides of the diaphragm at the periphery thereof and supporting the diaphragm in the housing, and rubber covered studs on the housing projecting into said openings.
9. The combination of a telephone receiver comprising a diaphragm and a magnet, a housing for the diaphragm, a support for the magnet, and a casing enclosing both said housing and said support, and protecting the face of said diaphragm.
10. The combination of a telephone receiver comprising a diaphragm and a magnet, a housing for the diaphragm, a support for the magnet, a casing enclosing both said housing and said support, and protecting the face of said diaphragm, and means connected to said magnet and projecting through the casing and adapted to be operated for adjusting the magnet and diaphragm relatively to each other.

BERKEY E. COVER.
